UNITED STATES PATENT OFFICE.

CHARLES E. BENTLEY, OF NEW YORK, N. Y.

DESIGN FOR A PILLOW-FACING.

SPECIFICATION forming part of Design No. 35,606, dated January 21, 1902.

Application filed November 18, 1901. Serial No. 82,800. Term of patent 3½ years.

To all whom it may concern:

Be it known that I, CHARLES E. BENTLEY, a citizen of the United States of America, and a resident of the borough of Manhattan, city of New York, State of New York, have invented and produced a new and original Design for a Pillow-Facing, of which the following is a specification, reference being had to the accompanying drawing, forming part thereof, and which is a plan view of a pillow-facing illustrating my design.

This design comprises a centerpiece or field 1 of round or rounded form and a foliated marginal portion having the outline of a series of leaf-like tabs 2, which radiate from the rounded centerpiece and taper outward at the edges toward their point or outer end.

Minor features of the design comprise a border or band 3, extending around the edge or margin of the centerpiece, and a border or band 4, extending along the edge of each radial tab 2 from its base to its point.

The more essential feature of the design is the round or rounded centerpiece surrounded by radiating and tapering leaf-like tabs 25 forming a foliated margin to the rounded centerpiece of the pillow-facing.

I claim as my invention—

The design for a pillow-facing, substantially as herein shown and described.

CHARLES E. BENTLEY.
